GOLF BAG

Joseph W. Osten, Chicago, Ill.

Application December 8, 1932, Serial No. 646,262

6 Claims. (Cl. 150—1.5)

My invention relates to a golf bag of the type commonly known as the stayless bag, and has particular reference to a golf bag construction in which a reinforcing member is formed for the handle construction, and also having means which prevent the bag from collapsing entirely when it is set or laid upon the ground.

Another and further object of my invention is the provision of a golf bag construction having a pair of stays placed therein in such manner that the bag at the handle portion thereof is reinforced and the weight of the bag distributed throughout a large portion of the body thereof at one side, instead of being concentrated at the point of the body of the bag to which the handle is attached, thereby resulting in the bag being pulled out of shape and causing abnormal wear on the body of the golf bag to which the handle is attached.

Another and further object of my invention is the provision of a golf bag having stays which extend throughout the upper portion of the bag on each side of and for some distance above and below the handle, and which are sufficiently stiff to prevent the upper part of the golf bag from collapsing when it is set on the ground, a common fault with the average stayless type of golf bag, which when set or laid upon the ground collapses from the top to a point below the centers of gravity of the golf clubs so that when the bag is picked up the weight of the golf clubs causes the bag to tip over and the clubs fall out onto the ground. With my improved construction this difficulty is avoided and the top of the bag will always remain sufficiently high on the golf clubs so that the bag and clubs can be picked up without danger of the clubs falling out onto the ground.

These and other objects of my invention will be more fully and better understood by reference to the accompanying sheet of drawings, in which—

Figure 1 is an elevational view of a golf bag embodying my invention;

Figure 2 is a sectional view throughout the body of the golf bag showing the stays secured therein;

Figure 3 is a fragmentary elevational view of the inside of the golf bag showing the stays positioned in the upper part thereof; and

Figure 4 is a cross sectional view on line 4—4 of Figure 3.

Referring now specifically to the drawing, and in which like reference characters indicate like parts throughout, a golf bag is shown having the

usual body portion 10, around the bottom of which a reinforcing member 11 is placed in the usual manner, with a top portion 12 being provided which is stitched to the body portion 10 of the bag in the usual manner. A ball pocket 13 is provided with a reinforcing strip 14 being provided which extends under the reinforcing member 12 at the top and down into the pocket 13, and is secured to the body of the golf bag by stitching or in any other approved manner. Between the reinforcing member 14 and the body 10 of the bag, adjacent the marginal edges of the reinforcing member 14, I provide a pair of metallic stays 15, 15, these stays being preferably of metal construction preferably about $\frac{3}{8}$ of an inch wide and $\frac{1}{8}$ of an inch thick. Near the bottoms of the stays 15 are a plurality of spaced openings 16, 16 through the body 10 of the golf bag and through which the members 15 extend. Similar slits 17, 17 are provided at the upper portion of the bag through which the reinforcing members extend adjacent their upper ends, so that they are held in proper spaced relation under the reinforcing member 14.

A handle 18 is provided which is secured through the reinforcing member 14 and the body 10 of the golf bag by means of rivets 19, 19 at its upper end and lower end, the handle 18 being riveted through the body of the bag between the reinforcing stays 15, 15.

The usual shoulder strap 20 is provided, which is secured by means of a buckle 21, with a loop 22 passing through the body of the golf bag and the reinforcing member 14 by means of rivets 19, 19 at the lower end, and is stitched through the reinforcing member on the body of the golf bag at its upper end in the usual manner of securing shoulder straps to golf bags. It will be noticed that both the shoulder strap 20 and the handle 18 are secured to the reinforcing member 14 and through the body 10 adjacent the stays 15, so that as the golf bag is lifted with either one of these members the weight is sustained largely upon the reinforcing stays 15 and thereby distributed throughout the upper portion of the golf bag rather than having the entire weight of the bag sustained from the upper and lower points of the handle 18 or the upper and lower points of the shoulder strap 20. In this manner the life of the golf bag is materially increased as well as its appearance, because stayless bags when carried by the shoulder strap or handle assume an elongated position and through wear and constant weight hanging on the straps and handles, the body of the bag is torn and presents an un-

sightly appearance. In addition to adding to the appearance of the bag, therefore, the life of the bag is also materially increased.

When the bag is set down on the ground or laid down by a player, the lower portion of the bag will collapse but the upper part of the bag is prevented from collapsing due to the stays 15, 15, so that the top of the bag will not slide down over the golf clubs to a point where, when the bag is picked up, it will tip and allow the clubs to slide out, as is common with stayless bags which are now in service. The top of the bag will remain sufficiently high on the golf clubs so that when picked up the clubs will remain in their proper position in the bag or will slide toward the bottom of the bag.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of the invention.

I claim:

1. A golf bag, a handle thereon, and stays on each side of the handle portion extending partially of the length of the golf bag and terminating near the longitudinal center of the bag.
2. A golf bag, a handle thereon, and stays on each side of the handle portion extending partially of the length of the golf bag and a short distance above and below the handle of the golf bag and terminating near the longitudinal center of the bag.
3. A golf bag, a reinforcing strip secured to said bag, a handle secured to the reinforcing member and the golf bag, stays interposed between the

body of the golf bag and the reinforcing member and extending a short distance above and below the handle on the reinforcing member and terminating near the longitudinal center of the bag.

4. A golf bag, a reinforcing strip secured to said bag and extending partially the length of the golf bag and terminating near the longitudinal center of the bag, a handle secured to the reinforcing member and the golf bag, and stays of substantially the same length as the reinforcing member interposed between the body of the golf bag and along the marginal edges of the reinforcing member.

5. A golf bag of the stayless type, comprising a body portion, a reinforcing member on one side thereof extending from the top of the bag partially along one side thereof, a handle secured to said reinforcing member and the body of the said bag, and stays on each side of said handle outside of the body and under said reinforcing member, and of substantially the same length as the reinforcing member, the said reinforcing member and the said stays terminating near the longitudinal center of the bag.

6. A golf bag of the stayless type, comprising a body portion, a reinforcing member on one side thereof extending from the top of the bag partially along one side thereof, a handle secured to said reinforcing member and the body of the said bag, and stays on each side of said handle outside of the body and under said reinforcing member, the said stays being held in spaced relation with each other and of substantially the same length as the reinforcing member, the said stays terminating near the longitudinal center of the bag.
